(57) **CLAIM**

The ornamental design for a combined terminal with charger, as shown and described.

DESCRIPTION

FIG. 1 is a front, side perspective view of a terminal showing my new design, the terminal is shown separately for purposes of illustration;

FIG. 2 is a rear, side perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is the front, side perspective view of a charger for the terminal shown in FIG. 1, the charger is shown separately for purposes of illustration;

FIG. 10 is a rear, side perspective view thereof;

FIG. 11 is a front elevational view thereof;

FIG. 12 is a rear elevational view thereof;

FIG. 13 is a right side elevational view thereof;

FIG. 14 is a left side elevational view thereof;

FIG. 15 is a top plan view thereof;

FIG. 16 is a bottom plan view thereof;

FIG. 17 is a front, side perspective view of the terminal of FIG. 1 shown in position in the charger of FIG. 9;

FIG. 18 is a rear, side perspective view thereof;

FIG. 19 is a front elevational view thereof;

FIG. 20 is a rear elevational view thereof;

FIG. 21 is a right side elevational view thereof;

FIG. 22 is a left side elevational view thereof;

FIG. 23 is a top plan view thereof; and,

FIG. 24 is a bottom plan view thereof.

The portions of the terminal and/or charger shown in broken lines form no part of the claimed design.
